UNITED STATES PATENT OFFICE.

SYLVANUS D. LOCKE, OF HOOSICK FALLS, NEW YORK, ASSIGNOR TO THE
LOCKE STEEL BELT COMPANY, OF NEW YORK, N. Y.

DESIGN FOR A CHAIN-LINK.

SPECIFICATION forming part of Design No. 30,363, dated March 21, 1899.

Application filed February 20, 1899. Serial No. 706,268. Term of patent 14 years.

To all whom it may concern:

Be it known that I, SYLVANUS D. LOCKE, a citizen of the United States, and a resident of Hoosick Falls, in the county of Rensselaer and State of New York, have invented and produced a new and original Design for a Chain-Link, of which the following is a specification, reference being had to the accompanying drawings, forming a part thereof.

10 The leading features of my design consist in a chain-link having a general rectangular shape and having the end bar at one end of the link formed of portions of unequal length curved over toward each other from the inner edge of the bar, one of said curved portions having a length approximately equal to the extreme width of the link and the other having a length approximately equal to the width between the side bars, the opposite end

15 bar of the link being also formed of two curved portions, each having a length approximately equal to the distance between the

two side bars and curved over toward each other.

In the accompanying drawings, Figure 1 ²⁵ represents a plan view of a link, and Fig. 2 represents an edge view of the same.

A A' represent the side bars of the link, B B' represent the curved portions of unequal lengths at one end bar of the link, and b b' ³⁰ represent the curved portions of equal length at the opposite end bar of the link.

What I claim is—

The design for a chain-link substantially as herein shown and described.

In testimony that I claim the foregoing as my invention I have signed my name, in presence of two witnesses, this 10th day of February, 1899.

SYLVANUS D. LOCKE.

Witnesses:

FREDK. HAYNES,
